Author to Earliest Bo

Design

PATENTED
JUN 15 1869

J. F. Beale
B. Kersting

United States Patent Office.

ISAAC N. ROSS, OF HOLDEN, MASSACHUSETTS, ASSIGNOR TO
EARLE STOVE COMPANY.

Design No. 3,553, dated June 15, 1869.

DESIGN FOR A COOK'S STOVE.

The Schedule referred to in these Letters Patent and making part of the same.

To all whom it may concern:

Be it known that I, ISAAC N. ROSS, of Holden, in the county of Worcester, and State of Massachusetts, have invented a new Design for the Castings for a Cook-Stove; and I do hereby declare the following to be a full, clear, and exact description of the same, reference being had to the accompanying drawings, in which—

Figure 1 represents, in perspective, a stove constructed in accordance with my design.

Figure 2 is a similar view of the same, with the doors open.

This stove belongs to that class of cook-stoves known as "square," or "low-oven" cook-stoves.

The oven has but one door at each end. The doors are all provided with raised panels, surrounded by deep mouldings and a row of ornaments.

In the centre of each panel is an oval shield, with lance-head radiations.

The stove is supported on four ornamented legs.

What I claim as my invention, is—

The design for stove-castings herein specified.

ISAAC N. ROSS.
